UNITED STATES PATENT OFFICE.

EDWARD I. PEARSON, OF TOLEDO, OHIO.

VAPORIZING CARBURETOR.

Application filed August 2, 1919. Serial No. 314,867.

To all whom it may concern:

Be it known that I, EDWARD I. PEARSON, a citizen of the United States, and a resident of Toledo, in the county of Lucas and State 5 of Ohio, have invented a certain new and useful Vaporizing Carburetor; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to means for use in connection with internal combustion engines to vaporize a liquid fuel therefor and mix it in suitable proportion with air preparatory to introducing into the engine.

20 The primary object of my invention is the provision of a simple, efficient and inexpensive vaporizing carburetor of the class described which utilizes the hot exhaust gases from the engine to effect a thorough vaporization of the liquid fuel employed to operate the engine, and which is so constructed that a minimum of vaporized fuel is carried to the engine or cylinders by the inrushing air with which it is mixed, thereby materially 25 economizing on the use of fuel.

The invention is fully described in the following specification and a preferred and modified form thereof is illustrated in the accompanying drawings, in which,

35 Figure 1 is an enlarged central vertical sectional view of the vaporizing carburetor taken on the line 1—1 in Fig. 2 with parts in full. Fig. 2 is a reduced section on the line 2—2 in Fig. 1. Fig. 3 is a section on the line 3—3 in Fig. 2, and Fig. 4 is a vertical section of the vaporizing carburetor similar to Fig. 1 with a float controlled 40 liquid fuel feed.

45 Referring to the drawings, 1 designates a casing of circular form transversely of its axis and of narrow or flattened form longitudinally of its axis, and which is formed at opposite sides of its axis with extensions 2 and 3 providing inlet and outlet passages 4 and 5, respectively, in connection with a mixing chamber 6 formed by the casing 1.

50 The mixing chamber 6 is made in the form of an annulus by the axial extension therethrough of a tubular wall or casing 7 forming a passage 8 and adapted to be connected with the exhaust port or manifold of

the associated engine so that the hot exhaust gases have their discharge through the mixing chamber and are spaced therefrom by the casing 7. The exhaust tube 7 is preferably at least as large in diameter as the inlet and exhaust passages 4 and 5 and is interposed therebetween so that substantially all of the air which is drawn through the device from the atmosphere is caused to have 60 contact with and be heated by the tube or casing 7.

65 The inlet passage 4 is provided with a control valve 9, which, in the present instance, is pivoted to the casing at one side of said passage and is adapted to be regulated to open the passage 4 to any desired extent. The device when in use is preferably placed with its central exhaust passage 8 horizontally disposed and the liquid fuel is introduced into the chamber 6 at the upper side of the exhaust tube 7 and preferably adjacent to the air inlet 4. In Fig. 1 a feed nozzle 10 is projected into and suitably connected with a feed nipple 11 which is threaded into or otherwise suitably connected to the casing 1 with its passage in communication with the upper rear portion of the mixing chamber 6, as shown. The nozzle 10 is connected to any suitable source of liquid fuel supply and the feed therethrough is controlled by a needle valve 12.

70 It is preferable in practice to provide a plurality of small air inlet passages 13 through the wall of the nipple 11 with 90 their inner ends opening adjacent to the discharge end of the nozzle 10 whereby the liquid as it passes from the nozzle is picked up and carried into the mixing chamber by the inrushing air and partially broken up 75 thereby. The liquid fuel as it is discharged into the mixing chamber 6 comes in contact with the hot exhaust casing 7 and with the heated air above the same and is quickly and effectively vaporized so that 80 it forms a vaporized fuel cloud in the upper portion or branch of the mixing chamber as designated by the scroll lines. It 85 is found in practice that the air as it rushes in and through the device from the inlet 4 instead of passing over the exhaust casing 7 and carrying the vaporized fuel 95 cloud with it, passes under said casing through the lower branch of the mixing chamber and has contact with the forward 100 end portion of the vaporized fuel cloud and only carries such portion with it into 105 110

the engine cylinder. This action effects a material saving in fuel and is found in practice to cause an efficient running of the associated engine.

5 A U-shaped tube 14 has one leg tapped into the bottom of the casing 1 in communication with the lower portion of the mixing chamber 6 for furnishing auxiliary air and has its other end opening to the atmosphere and terminating substantially on a plane with the lower edge of the exhaust casing 7 and below the bottom plane of the passages 4 and 5. Preparatory to starting the engine a small quantity of liquid fuel is permitted to accumulate in the lower portion of the mixing chamber 6 and in the tube 14. Upon starting the engine the air is drawn into the mixing chamber through the tube 14 and up through the liquid fuel in the bottom of said chamber so that the air is saturated with the fuel and the fuel is partially vaporized by the rushing of the air therethrough. When the engine has been run a very short time the exhaust casing 7 through the device becomes highly heated so that the fuel discharging into the mixing chamber is thoroughly vaporized and carried to the cylinder in such form. The main air inlet valve 9 should then be opened the desired extent to permit the desired quantity of air to enter and pass through the mixing chamber as the efficient running of the engine may require.

35 In Fig. 4 the liquid feed to the mixing chamber of the device is through a float chamber 15, the feed of fuel to which is controlled by a float valve 16, as well understood in the art. In this form of the invention the outer end of the air inlet extension 2 is directed downwardly, as shown at 17, and the outer end of the inlet passage 4 therethrough is normally closed by a valve 18 which is adapted to open inwardly under the engine suction against the tension of a closing spring 19. A lever 20 is fulcrumed in the passage 4 and has one end provided with a valve 21 adapted to close the passage 22 between the float chamber 15 and the mixing chamber 6 of the carburetor while the other end of the lever is in engagement with the inner side of the valve 18 whereby an inward or opening movement of said valve imparts movement to the lever 20 and a consequent opening of the valve 21. A spring 23 acts on the lever 20 to normally retain its valve 21 in closed position.

60 The design of vaporizing carburetor which I have shown is adapted particularly for use on a single cylinder engine, the outlet extension 3 of the carburetor being angled to adapt it for connection with the inlet port of the cylinder and the tube 7 being positioned and adapted at its inner

end for connection with the exhaust port of the cylinder. It will be understood, however, that the parts 3 and 7 may be suitably arranged and adapted for connection with the respective inlet and exhaust manifolds of an engine of the multiple cylinder type.

It is found in practice that a very efficient and economical running of an engine can be obtained by the use of my improved vaporizing carburetor on account of the thorough vaporization of the liquid fuel in the mixing chamber and the manner of passage of the mixing air through said chamber so that the fuel vapor instead of being bodily carried to the engine by the suction action of the air rushing through the mixing chamber is only partially carried thereto by the sweeping action which the inrushing heated air has against the forward edge portion of the vaporized fuel cloud, as illustrated crudely in Fig. 1.

I wish it understood that my invention is not limited to any specific construction, arrangement or form of the parts as it is capable of numerous modifications without departing from the spirit of the claims.

Having thus described my invention, what I claim as new, and desire to secure by Letters Patent, is,—

1. In a vaporizing carburetor, means forming a passage for exhaust gases and a passage around said first passage transverse to its longitudinal axis and adapted to have communication at one side of the exhaust passage with the atmosphere and at the other side of the exhaust passage with an engine cylinder, and means for introducing liquid fuel into said second passage and against the wall of the exhaust passage at one side of a plane which is longitudinal to the exhaust passage and extends therefrom centrally of the main air inlet end of the second passage.

2. In a vaporizing carburetor, means forming a cylindrical passage for exhaust gases and a passage around the exhaust passage transverse to its longitudinal axis and adapted to have valve controlled communication at one side of the exhaust passage with the atmosphere and at the other side thereof with an engine cylinder, means for introducing liquid fuel into the second passage and against the wall of the exhaust passage at one side of a plane longitudinal to the exhaust passage axis and radially therefrom centrally of the air inlet end of the second passage whereby the liquid fuel

110 will be vaporized in one branch of the second passage at one side of the exhaust passage and air will pass through another branch of the second passage at the opposite side of the exhaust passage, and a U-shaped tube having one end opening into the bottom of the second passage below

the exhaust passage and its other end open to the atmosphere at a point above the other end of the tube.

3. In a vaporizing carbureter, means forming a valve controlled air passage adapted to have communication at one end with the atmosphere and at its other end with the vaporized fuel intake of an engine, said passage having an annular enlargement intermediate its ends with its axis transverse to the pipe, an exhaust pipe extending through the air passage enlargement axially thereof, the pipe being substantially the size of the intake end of the air passage and dividing the enlargement thereof into two branches of substantially equal size which merge at opposite sides of the pipe, and means for introducing liquid fuel into one of said branches intermediate its ends whereby vaporized fuel passes through one branch and air passes through the other branch of the air passage.

4. In a vaporizing carburetor, means

forming an air passage adapted to have communication at one end with the atmosphere and at its other end with the vaporized fuel intake of an engine, an exhaust pipe extending transversely through said passage intermediate its ends to intercept air in its passage therethrough and dividing the passage into separate upper and lower branches having their ends merging at opposite sides of the exhaust pipe, means for introducing liquid fuel into the upper branch of the passage intermediate its ends whereby the vaporized fuel substantially fills and passes through the upper branch and the inrushing air passes through the lower branch and mixes with the vaporized fuel at the engine intake side of the exhaust pipe, and a pipe forming an auxiliary air inlet opening into the bottom of the lower branch and having its inlet end disposed above its outlet end.

In testimony whereof, I have hereunto signed my name to this specification.

EDWARD I. PEARSON.
